(57) **CLAIM**

The ornamental design for a vehicle wheel, as shown and described.

DESCRIPTION

FIG. 1 is a perspective view of a vehicle wheel showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a cross-sectional view thereof taken along the line **8-8** of FIG. 2; and,

FIG. 9 is another front view thereof.

The broken line of screws in FIGS. 1-2 and 8-9 illustrates unclaimed environment and forms no part of the claimed design. The broken line portions of the vehicle wheel in FIGS. 1-3, 5 and 7-9 represent unclaimed portions of the claimed design and form no part thereof.

1 Claim, 8 Drawing Sheets**FIG. 1**

FIG. 2

FIG. 3

FIG. 4

FIG. 5

FIG. 6

FIG. 7

FIG. 8

FIG. 9
